DESIGN FOR A TIRE

Elmer F. Brunner, Silver Lake, Ohio, assignor to Wingfoot Corporation, Wilmington, Del., a corporation of Delaware

Application December 1, 1937, Serial No. 73,299

Term of patent 14 years

To all whom it may concern:

Be it known that I, Elmer F. Brunner, a citizen of the United States, residing at 81 Hastings Road, Silver Lake, in the county of Summit and State of Ohio, have invented a new, original, and ornamental Design for a Tire, of which the following is a specification, reference being had to the accompanying drawing, forming part thereof.

Fig. 1 is a perspective view of a tire casing showing my new design; and

Fig. 2 is a cross-sectional view taken on the line
2—2 of Fig. 1.

I claim:

The ornamental design for a tire, as shown.
